VENETIAN BLIND HEAD BAR

Samuel Hammer, Brooklyn, N. Y., assignor to
United Metal Box Co., Inc., Brooklyn, N. Y., a
corporation of New York

Application October 17, 1936, Serial No. 106,096

13 Claims. (Cl. 156—17)

This invention relates to Venetian blinds for windows, and the object is to improve the head bar construction; the slat tilting and locking mechanism; the construction of the housings for the tilting and locking mechanisms; and to provide a construction in which the housings are assembled on and supported by the head bar by telescoping the housings into the head bar. Also to provide a tilting mechanism which will retain the slats at adjusted angles; a head bar construction which will provide the maximum spread of blind slats and minimum exposure of working parts; a construction which will permit assembly of the parts without welding, soldering, riveting or bolting; a structure which will permit assembly of the parts either at the place of manufacture or place of installation; a structure which will permit complete assembly of head bar, tilting and locking mechanism housings, slats, tilting and elevating cords preparatory to hanging on supporting brackets and permitting final adjustment and locking of the head bar and suspended slats in adjusted position within the sides of a window casing without disturbing or rearranging the assembly of parts; and generally to provide a structure of smooth and finished appearance.

My invention is illustrated in the accompanying drawings in which

Figure 1 is an elevation showing a window casing with the improved blind in position and showing particularly the location of the head or supporting bar with respect to the window casing and the spread of the blind slats between the upright members of the casing.

Figure 2 is an enlarged front elevation of the head bar, supporting brackets, tilting slat and slats suspended therefrom to show the complete assembly, part of the lowermost slat being in section to show a detail of the construction.

Figure 3 is an enlarged plan view of one end of the lowermost slat showing the anchor for the elevating cord.

Figure 4 is a top plan view and partial section of the head bar and supporting brackets.

Figure 5 and 6 are vertical cross-sections on the lines 5—5 and 6—6, respectively, of Figure 4.

Figure 7 is a side elevation of the slat tilting mechanism with part of the housing removed and the tilting gear segment shown in dotted lines in tilted position.

Figure 8 is a vertical section on the line 8—8 of Figure 7.

Figure 9 is a perspective view of the head bar and housings illustrating the mode of assembly and the manner of supporting the housings with-

in the head bar by telescoping the housings into the head bar.

Figure 10 is a side elevation of the housing for the locking mechanism.

Figure 11 is a plan view of the single plate 5 stamping before bending into shape which constitutes the entire locking mechanism housing.

Figure 12 is an elevation illustrating the suspension for blinds of extra width and showing a central support for the tilting slat.

Figures 13 and 14 are enlarged vertical cross-sections on the lines 13—13 and 14—14, respectively, of Figure 12.

Referring to the drawings, and more particularly to Figure 1, a window is illustrated having 15 a casing comprising the usual sill 1, side frames 2 and 3, top rail 4, and sash 5. The Venetian blind is indicated by slats 6, suspended by elevating cords 7 from a head bar 8 which is mounted on brackets 9; the slats 6 being also suspended from the tilting bar or slat 10 by tilting and suspension tapes 11. Tilting cords 12 are attached to a tilting mechanism carried by housing 13. Elevating cord guides, lock and roller are disposed in housing 14. The pivots for tilting slat 10 are in the 20 housings 13 and 14. When the blind slats are lowered the full length with the window open, the blind is held against swaying by hooking the anchor ends 7a of the elevating cords 7 over sill hooks 1a and then drawing the elevating cords 25 taut and locking same at the housing 14 as hereinafter explained.

Referring now to Figures 2 to 6 and 9, and more particularly to the head bar construction, it will be seen that the head bar is in the form of a channel bar stamped from sheet metal with preferably a straight even bottom or web 15, front and rear flanges 16 and 17 stamped with longitudinal depressions 18 and 19, and longitudinal inwardly projecting flanges 20, the flanges 16 and 17 serving to prevent bending or sagging of the head bar due to the weight of the slats suspended therefrom, and the depressions 18 and 19 and flanges 20 serving as guides and retaining means as will hereinafter appear. The head bar is open at both ends, and the web 15 is cut back at both ends to provide a space between the projecting flanges 16 and 17 equal to the depth of the housings 13 and 14 as best seen in Figure 9. The flanges 16 and 17 at both ends have tongues 21 projecting beyond the ends of the flanges which are adapted to be bent over the housings 13 and 14 when the head bar, housings, tilting slat 10, and the elevating and tilting cords are assembled as shown in Figure 2, to hold those parts together firmly and in 50 55

proper alignment without any other fastening means pending final hanging, adjustment and clamping on brackets 9. At each end of the front flange 16 of the head bar is a round hole 22* (see Figure 9) to permit entrance of a screw 22, and at each end of the rear flange 17, approximately the full width of the depression 19, is an elongated rectangular hole 23, see Figures 2, 4 and 9, the purpose of which will be hereinafter referred to.

10 In the web 15 are two rectangular holes 24, both cut at an angle to the longitudinal center of the head bar, through which elevating cords 7 pass downward and through holes in slats 6 for attachment to the lowermost slat 6 for raising and lowering the slats. At each hole 24 a roller 15 25 is journaled in a bearing block 26 stamped from sheet metal and having a pair of upwardly projecting flanges 27, one flange having a round hole for one journal of roller 25 and the opposite flange having a slit 28 in alignment with the hole and having a rounded bottom to form the bearing for the other journal of the roller 25. Adjacent slit 28 is another slit 29, not as deep as slit 28, forming a tongue 30, which, when the roller 25 is in place between the flanges 27, is bent over the journal to prevent displacement of the roller from the block, see Figure 4. The web of roller block 26 is punched out to form a rectangular opening corresponding to hole 24 in the head bar 20 web, and the metal punched out is bent down 30 to form two flanges 31 which project through the hole 24 and are bent over flat against the underside of web 15 to secure the roller block in position as seen in Figure 2. It may be here noted 35 that the holes 24 are punched in web 15 at definite points and at definite angles relative to the center line of each standard length head bar and slats to go with such head bar, so that the axes of rollers 25 when set in position will be exactly perpendicular to the elevating cords extending horizontally within the head bar as seen in Figures 2 and 4. It will also be noted that a roller is employed in preference to the usual grooved sheave, and that the roller is relatively 40 long, and that hole 24 is quite large relative to the diameter of cord 7. This construction presents a smooth curved surface formed by flanges 31 at each side of the hole 24 under and adjacent the ends of the roller and reduces, to a minimum, wear of the cord. By the simple arrangement of the square holes 24 cut at the desired angle relative to the center line of the head bar, and the parallel flanges 31 on bearing blocks 26, the rollers 25 may be set and secured at the correct angle for cords 7 without other adjustment 45 or fastening means.

The web 15 of the head bar is cut out at each end as above stated the full width between the flanges 16 and 17 to a depth equal to the thickness of housings 13 and 14 (see Figure 9) to permit telescoping the housings into the head bar between the flanges 16 and 17 with the outer walls of the housings flush with the ends of the flanges so that tongues 21 may be bent over inwardly at right angles and flush against the outer walls of the housings as best seen in Figures 2 and 4. This locking by tongues 21 plus a feature in the construction of the housings 13 and 14 hereinafter referred to constitute the sole means for securing the housings upon the head bar, thus dispensing with soldering, welding, riveting, bolts or screws in assembling the head bar and housings, and permitting quick assembly or disassembly for replacement of cords or other parts 50 when necessary. The construction of the hous- 55

ings and the mode of assembly upon the head bar is such that tongues 21 are not necessary to hold the housings in position after the blind is hung and secured on the hanging brackets 9. The tongues are only essential for securing the 5 housings in position when the assembling is done at the place of manufacture.

The housing 13 which carries the tilting mechanism is stamped from sheet metal in two parts, one part having a wall 32, front flange 33, rear flange 34, and bottom flange 35, the top being entirely open, see Figures 4, 5, 7 and 8. Front flange 33 has a rectangular shaped wing or extension 36 of a width to make a close sliding fit between web 15 and flange 20 of the head bar, 10 and of a length to insure holding the housing against tilting movement on the head bar due to the weight of the blind slats or the pull of the tilting cords. The front flange 33 is stamped out close to the wall 32 to form a square recess 37, 15 the center of the square being coincident with the center of the screw hole 22* in depression 18 of the head bar flange 16, see Figure 9. The metal stamped out to form recess 37 is bent inward to form L-flanges 38, see Figure 7, of a 20 depth to receive flush and form a seat for a square screw-threaded nut 39, see Figure 9, into which screw 22 is threaded when the parts are finally assembled and adjusted on brackets 9 as seen at the left end of Figure 4, and as hereinafter more specifically referred to. The rear flange 34 of the housing has a wing 40 of the same shape and dimensions as wing 36 on the front flange, and this wing has a long rectangular hole 41 corresponding in width and length 25 to the hole 23 in the rear flange depression 19 of the head bar and which holes register when the housing 13 is fully telescoped into position on the head bar as seen in Figures 4 and 9. The bottom flange 35 of the housing is severed 30 from wall 32 at its forward end, and this severed end is perforated centrally of its width with a small hole and bent back on the line of such perforation as shown at 42 in Figure 7. This bend 42 forms a guide for tilting cords 12 and a guard 45 for the end of pin 43 which is driven with a tight fit through a perforation in flange 33 and through the perforation in guard 42 as seen in Figure 7. The width of flanges 33 and 34 is such to form a box of a depth to freely accommodate 50 the two tilting cords which are held spaced by pin 43 as seen in Figure 4, and which pin prevents the cords from twisting as they are drawn into and out of the housing in tilting the slots. The housing is completed by a cover section 44 55 stamped from sheet metal to make a close fit between flanges 33 and 34 and having top and bottom rectangular flanges which bear against the wall 32 as seen in Figure 8. The lower flange of the cover is cut away at the forward end to 60 provide an opening for the passage of cords 12 into the housing, and this flange seats on flange 35 between the bend 42 and rear flange 34. At approximately the center of cover 44 a circular depression is stamped out as shown at 45, see Figures 2, 5 and 8, the metal being cut through on the lower half of the circle thereby forming a lug or ear, and the center of the depression has a hole punched through to form a bearing for the journal 46 of pinion 47. The wall 32 is perforated at 70 its center in alignment with the perforation in depression 45 to form the opposite bearing 46 for pinion 47. This pinion is made from stock pinion rod with reduced journal ends and is of a length to fit between wall 32 and depression 45 and has 75

two functions. One function is to serve as a spined shaft or hub for disk 48, and the other as a pinion for imparting rotary movement to gear segment 49 which is mounted on the outside of housing 13 on a pivot pin 50 inserted through holes in the cover plate 44 and wall 32. This pivot pin is in the form of a rivet and serves also to hold the cover plate in position at the bottom, and at the upper part the cover is locked in position by slight angular bends 36^a and 40^a given to the lower inner edges of wings 36 and 40 as seen in Figures 5 and 8.

Disk 48 shown in detail in Figure 7 is a plate of sheet metal having its center punched out with notches to engage the splines of pinion rod 47, and radial punchings 51, eight being shown, bent outwardly and alternately on opposite sides of the disk, to form lugs or hooks around which tilting cords 12 are wound in opposite directions. As seen in Figure 7, cords 12 are threaded through the opening at the front lower corner of housing 13 and coiled on hooks 51 in a flat spiral of two convolutions in opposite directions on opposite sides of the disk, the ends of the cords being held by slightly pinching the first engaging hook. In the position shown in Figure 5, the slats are held in the horizontal position by gear segment 49, the coils of the cords 12 being shown in dotted lines. When either cord 12 is drawn downward, disk 48 is rotated, unwinding the cord on one side of the disk and winding up on the other side. As seen in Figure 7, the cord shown in full lines is in front of the disk and has been unwound, thereby turning the disk clockwise and the gear segment counter-clockwise to the position shown in dotted lines, and the cord behind the disk having been wound up as indicated in dotted lines. This rotation of the disk rotates pinion rod 47 which in turn rotates segment 49, and thereby tilting slat 10, the full rotary movement being slightly less than ninety degrees as seen in Figure 7, and the movement being limited in either direction by stop teeth 52 on the gear segment and which teeth are longer than the segment teeth thereby arresting the rotation of the segment when either tooth 52 engages the pinion 47.

Owing to the fact that tilting slat 10 is pivoted centrally on its longitudinal axis, and therefore balanced by the suspended slats 6, and owing to the large difference in pitch diameters of segment 49 and pinion 47, slats 10 and 6 will readily remain in any adjusted angle, but in order to insure maintenance in the adjusted position against air currents and any attempt to change the adjustment by direct tilting of the slats by hand, I provide a light brake for disk 48 in the form of a bow spring blade 53, see Figure 7. The curved ends of this spring bear against flange 34 of the housing and the bow contacts with the peripheral edge of disk 48 exerting a slight pressure thereon. With this slight pressure on the disk and the difference in pitch diameters of pinion 47 and segment 49, the pinion 47 will act as a stop for the gear segment and readily maintain the slats in any adjusted position. When a pull is exerted on either cord 12, however, the leverage is reversed and the braking action of spring 53 is readily overcome, and pinion 47 will readily rotate the segment to adjust the slats.

The housing 14 for the elevating cord guides and lock as shown in detail in Figures 10 and 11 is stamped from a single piece of sheet metal and bent into box-like form. The main section

which forms end wall 54 is bent at right angles on the dotted line *a* to form the bottom of the housing, and upward on line *b* to form a retaining flange 55. At the rear, the end wall 54 is bent at right angles on the line *c* to form the rear wall 56, and this flange is extended at the top to form rectangular wing 57 having a rectangular hole 58 corresponding in size to hole 23 on the head bar flange depression 19, and said wing and hole corresponding to the wing and hole 40-41 on housing 13 as seen in Figures 4 and 9. The front end of wall 54 has two extensions 59 and 61, severed by a cut 60, and these extensions are bent at right angles on the line *d* to form the front wall and also a wing 59 of the same shape and size as wing 57. Extension 61 is bent over at a right angle on the line *e* to form inside wall 61 and bent again at a right angle on the line *f* to form flange 62, and a final right angle bend on the line *g* to form flange 63, the two flanges 62 and 63 serving as spacers between end wall 54 and inside wall 61, and the inside wall 61 being retained in position by flange 55. The front wall section at the wing portion 59 is stamped out to form a recess 37 and L-flanges 38, similar to the recess 37 on housing 13, to receive a square screw-threaded nut 39 which will register with hole 22^a at the right-hand end of the head bar to receive a screw 22. The lower front corner of housing 14 is cut away to form the entrance for cords 7 as seen at 64 in Figures 2, 6 and 10. This cut out is formed by the irregular cut indicated by line *h* in the metal blank of Figure 11 and extends from flange 55 to flange 63, so that when the blank is bent into form as above described, the cord entrance 64 is formed. The bottom wall of the housing and the inside wall 61 are each perforated at a point midway of the opening 64 as indicated at *i* in Figures 10 and 11, through which perforations a headed pin 65 is inserted and its end bent over to retain it in position as seen in Figure 6. This pin holds cords 7 in spaced relationship and prevents twisting as the cords pass up and down through the opening 64. The end wall 54 at a point beginning in line with the upper edge of wall 61 has two vertical shifts *k* through which the arms 66-67 of a U-shaped bracket are inserted. This bracket is made from flat strip metal bent at right angles to form a flat cross piece which will lie close to the wall 54 when the bracket arms are projected through the wall as seen at 68 in Figure 4. When housing 14 is placed in position on the head bar by telescoping wings 57 and 59 between web 15 and flanges 20 as seen in Figure 4, bracket arms 66-67 will rest on web 15 as seen in Figure 6. This bracket is provided with a hole and slit to form bearings for roller 69 over which elevating cords 7 pass from housing 14 to rollers 25 on the head bar. This roller is located with respect to the housing 14 and web 15 of the head bar so as to be in alignment with opening 64 at the bottom of the housing. The bearings and retaining means for roller 69 on arms 66-67 are exactly similar to the bearings for rollers 25 and therefore detailed description of same need not be here repeated.

The locking means for the elevating cords 7 comprises two curved indentations 70 and 71 in walls 54 and 61 of housing 14, as seen in Figures 2, 6 and 9, and a wedging roller 72. The length of indentations 70-71 as seen in Figure 6 will be such as to insure contact with the pair of cords 7 in passing to roller 69 and their depth 75

and the diameter of roller 12 will be such as to insure wedging of the cords to sustain the weight of slats 6. While I have shown two oppositely set depressions 70-71, a single depression 71 may be employed. The wedging roller 12 will be of a length sufficient to bridge the pair of cords 7 or about the same length as depressions 70-71 and loosely positioned to engage the cords, but in order to avoid providing guides for the roller, or other means to prevent its becoming displaced, I employ a roller in the form of a long pin which preferably extends the width of the housing 14 between front and rear walls 54 and 61, a cut out 1 in flange 62 being provided through which the end 13 of the roller projects and which serves as a bearing for the roller pin as seen in Figure 6. The roller pin rests loosely at the bottom of the housing between cords 7 and wall 54 and is of such diameter that when the cords hang or are held straight down from opening 64, the cords will be in contact with the roller pin, and within the housing the cords will be caused to curve over into the path of vertical movement of the pin due to their contact with depression 71 as seen in Figure 2. In drawing the cords downward to raise the blind slats, the cords travel over rollers 25 and 69 and in contact with depression 71, and if the cords are held straight, that is, parallel with window casing 3, they will rotate the pin 12 without, however, causing any locking action. When it is desired to hold the blind slats at any elevated position, the cords are held toward the casing 3 and allowed to move upward due to the weight of the slats suspended therefrom, and this movement will cause the roller pin to rotate in a clockwise direction as viewed in Figure 2, and travel upward with the cords until the cords bind between depression 71 and the pin, whereupon the weight of the slats tending to draw the cords upward will increase the gripping effect by jamming the cords and roller pin between the depression 71 and wall 54, or when the second depression 70 is provided, the cords and roller pin will jam between the two depressions as shown in dotted lines in Figure 2. To release the lock preparatory to raising or lowering the slats, cords 7 are drawn downward slightly and swung toward the left, that it at an angle to the housing 14. This movement will release the grip on the roller pin and permit the pin to drop to its horizontal position in the housing, and while the cords are still held to the left, they may be allowed to move upward to lower the slats or be drawn downward to raise them. To again lock the cords to hold the slats in a readjusted position, the cords are swung back toward the casing 3 and allowed to move upward, whereupon the gripping action above described will be repeated.

In effecting the locking of the cords 7, a slight drop of the slats occurs until the cords are firmly gripped between the depression 71 and roller 12. To reduce this drop and practically effect an immediate gripping, I provide the second depression 70 which is located lower than the depression 71 and causes the roller to ride toward the vertical center of the housing and hastens the bending of the cords under depression 71 and consequently effecting a more rapid binding between the cords and roller. For the purpose of increasing the gripping effect and to make certain the pick-up of the roller by the cords 7, the end of the roller pin which overlaps the cords is knurled. It will be observed by reference to Figure 6, that while the end 13 of the roller pin rests

loosely in the notch 1 in flange 62, this rest not only constitutes a retaining means for preventing displacement of the roller pin, but also serves as a pivot whereby the entire weight of the long pin will operate quickly to return the gripping end to its unlocking position, that is, the horizontal position of the pin, when the cords 7 are drawn downward, thereby preventing inadvertent locking of the cords before the slats are adjusted to the desired elevation.

The tilting slat 10 is detachably mounted between gear segment 49 and pivot bar 75, the latter being pivoted on housing 14 by pivot pin 76. Segment 49 and bar 75 each has a pair of laterally projecting wings 77 and 78, respectively, as seen in Figures 5 and 6. As shown in dotted lines in Figure 4, and in solid line in Figure 9, wings 77 are curved as indicated at 77^a to afford clearance for segment stop teeth 52 and pinion bearing 45, and wings 78 have right angle cut outs as indicated at 78^a to clear the edge of the flare given to the wall of housing 14 at the opening 64, and also to clear the cords 7 when the slat 10 is tilted. Slat 10 at both ends is cut away at both the outer edges as indicated in Figure 9 at 10^a, and at the center line as indicated at 10^b, and as shown in dotted lines in Figure 4, to clear, respectively, the pinion bearing 45 and the head of pivot pin 50 at housing 13, and the flare at opening 64 and pivot pin 76 at housing 14. These cut out clearances on slat 10 are made alike at both ends of the slat to simplify assembly on the wings 77 and 78. The inner edges of the hollow beads 10^c on slat 10 are cut away at both ends of the slat to a point indicated at 10^d in Figure 2 to permit entrance of wings 77 and 78 into the beads as seen in Figures 5 and 6. It will be observed that the spread of wings 77 and 78 is such that the ends fit closely between the beads as seen in Figures 5 and 6, and it will be understood that the clearances at the ends of the beads for the entrance of the wings is such that the wings will slightly flex the beads in entering so that a sufficient tension is created to firmly hold the upper surfaces of the wings in close contact with the underside of slat 10 and thus prevent lost motion between the slat and pivot members 49 and 75. This construction of the tilting slat and wings on the pivot members permits assembly by a simple telescoping movement requiring no other fastening means when the head bar and tilting slat are assembled.

The tilting slat 10 and each of the slats 6 suspended therefrom are perforated for the passage of the elevating cords 7, and the lowermost slat 6 is provided with anchor plates 79 stamped from sheet metal with a slotted cavity or pocket 80 and a hole which is drawn out to form a ferrule 81 which fits the hole in the slat and is spun over, as shown in Figure 2, to secure the anchor plate to the underside of the slat. The elevating cords pass through ferrules 81 and the ends are knotted as at 82 and the knotted ends are slipped into the pocket 80.

In Figure 12 is shown an arrangement of compound elevating cords for a blind of extra width. In this arrangement the head bar 8, tilting mechanism and housing 13, elevating cord rollers 25 and 69, locking mechanism and housing 14, tilting slat 10, etc. are similar to the arrangement shown in Figure 2. But, in this arrangement the rollers 25 are spaced further apart and a single anchor plate 79 having two slotted pockets 80 and one ferrule 81 is provided on the head bar, and the lowermost slat 6 is provided with two rollers 75

25 mounted and secured in the same manner as described in connection with Figures 2 and 4, and a third roller bearing 83 secured in the same manner, but having two rollers 84 with the hole 5 for the cords 7 located between the rollers. The elevating cords are threaded up through housing 14 as in Figure 2, then over roller 69, then over rollers 25 on the head bar and down through the slats 10 and 6, then over the lower rollers 25 and 10 84 and up through the slats to the anchor plate 79 on the head bar. With this arrangement a third or intermediate tape 74 is employed and connected with the slats in the same manner as above described, and this tape, as do the other 15 tapes, serves to cover the cords 7 passing through the slats. In this arrangement for wide blinds the weight on the head bar and tilting slat is distributed and the pull on the cords is reduced.

For the purpose of supporting the tilting slat 20 at the mid-section to prevent sagging and reduce the tendency to twist, especially in wide blinds having extra length slats, I provide one or more hangers 85 (Figure 12) and shown in detail in Figure 13. When one such hanger is employed 25 it will be located at approximately the middle of the head bar, and when two are employed they will be suitably spaced from the center. In Figure 13 the hanger comprises a heavy wire 86 bent into an arch and having its ends welded or otherwise rigidly secured to the tilting slat 10 near the edge as shown in Figure 13, and a bracket 87 attached to web 15 of the head bar. The bracket may have a pin or roller 88 on which the arch 86 is hung, and the curve of the arch is such that 30 uniform contact will be maintained on the roller 35 at all angles of the tilting slat 10.

The brackets 9 for hanging the blind as shown 40 are left and right-hand, and each bracket comprises a main body 89 provided with screw holes 45 for securing the bracket to the side frames 2, 3 of the window casing, a rear flange 90 projecting at right angles to body 89 and likewise provided with screw holes for securing the flange to the angle of the window casing adjacent the sash, 50 and a top flange 91 projecting at right angles from body 89 and also provided with screw holes 55 for securing the bracket to the top rail 4 of the casing. By this arrangement of body and flanges, the bracket may be secured at any one of three 60 sections of the casing or at any two or all sections, according to the construction of the window casing, and the size and weight of the blind, and the flanges 90 and 91 serve an additional 65 purpose as will presently appear. The top flange 91 has an extension 92 bent at right angles to the flange and this extension is cut to provide a hook 93 projecting rearward toward, but spaced from, the rear bracket flange 90 as seen in Figures 4, 5 and 6. The front end of body 89 has a projection 60 94 bent at right angles to the body, and this projection is stamped with a depression 95 and slot 96 as seen in Figures 2 and 4. The depression 95 is stamped to match and seat into depression 18 on head bar wall 16 and the slot to register 65 with the hole for screw 22. The entire bracket as seen is stamped and bent into shape from a single piece of sheet metal.

When the head bar and housings with slats 10 and 6 and elevating cords are completely assembled as seen in Figure 2, the blind is hung on 70 brackets 9 by first placing the head bar with its rear wall against bracket flanges 90 and then sliding the head bar upward against the top flange 91. In this movement, the extensions 92 with hooks 93 will pass into the open top of the

head bar and bring the hooks into alignment with rectangular holes 23-41 and 23-58. The head bar is then moved forward, the top flanges 91 of the brackets serving as guides, to bring the front wall 16 against the front projections 94 of the 5 brackets. In this movement, hooks 93 pass through holes 23-41 and 23-58 and the head bar is then lowered to allow the rear walls to rest on the hooks as seen in Figures 5 and 6. The entire structure will now be suspended from the 10 hooks and permit easy adjustment of the head bar with the suspended slats longitudinally within the window casing without other support. When properly aligned, screws 22 are inserted through slots 96 in the bracket projections 94 15 and screwed into nuts 39, which, when screwed up tight, will draw the head bar and projections 94 tightly together with depressions 95 and 18 interlocking. The head bar and housings with the suspended slats will now be suspended in 20 fixed position from hooks 93 at the rear and locked at the front to bracket arms 94 by screws 22. Thus, by providing recesses 37 in housings 13 and 14 into which nuts 39 are seated and retained by flange 16 of the head bar when the 25 housings are telescoped into the head bar, and the use of two screws 22 which pass through bracket arms 94 and head bar flange 16, the entire structure is locked to the brackets in adjusted position within the window casing. To remove 30 screws 22 and slide the head bar backward and lift it off the hooks 93. For ornamental purpose, the heads of screws 22 may be of any desired 35 design.

The construction of the blind slats and the mode of connecting them with the tilting and suspension tapes 74 is similar to the construction and arrangement shown in my application Serial No. 18,300, filed April 26, 1935, now Patent 2,074,- 40 842, Mar. 23, 1937, and therefore it is sufficient to say that tapes 74 have loops in which staples 74a are hung and the ends of the staples are inserted through holes in the edges of beads 10c on the slats and bent to retain them in engagement with the slats. 45

As a specific mode of attachment of the tilting tapes 74 to the top and bottom slats, Figures 13 and 14 show the tapes 74 having loops 97 threaded through heavy staples or links 98 of sufficient width to receive the entire width of the tape and having their ends hooked into beads 10c. Near the ends of loops 97 are staples 74a which are inserted into the bead 10c of the adjacent slat, the legs of the staples entering the same holes as the staples of the tape section 74 as seen in Figure 13, and the loose end 99 of the loop being turned in to lie on the upper side of slat 6. At the bottom slat 6 the loop 97 will be carried up to the next higher slat 6 and the staples near its end will be hooked into the slat bead in the same manner as illustrated in Figure 13 except that the loose end will lie against the under side of the slat 6. This mode of connection reduces the strain on the upper and lower connections of the tape to the slats 10 and 6; avoids the necessity for finishing the ends of the tapes to prevent ravelling of the fabric; and provides a more finished appearance to the tape ends as will be seen by reference to Figure 1. 70

To finish off the bottom slat and conceal the elevating cords, rollers and anchors, I provide a shell 100 shown in Figures 12 and 14. This shell is removably attached to slat 6 by springing beads 101 into the recesses formed by slat beads 75

10^c which for this purpose are not bent in close against the under side of the slat as is the case with the rest of the slats, but are bent to present a flange substantially parallel to the body of the 5 slat as seen in Figure 14. By this means, the under side of the lower slat when the blind is in elevated position will present a smooth finished appearance with the elevating cords, rollers and anchors entirely concealed.

10 From the foregoing description and drawings, it will be seen that a construction and assembly of parts has been devised for Venetian blinds which permits production of an all metal blind, in other words the head bar and hangers are 15 constructed from sheet metal stampings capable of complete assembly ready for hanging without welding, soldering, riveting or bolting, and capable of complete disassembly for repair or change of parts without cutting or damage to any of 20 the parts. Furthermore, it will be seen that a construction has been devised permitting shipment of parts partially assembled or in wholly disassembled condition capable of complete assembly at the place of installation without the 25 use of special tools and by unskilled persons. Furthermore, a head bar construction has been devised capable of quick assembly into a complete, rigid and perfectly aligned structure, with minimum effort, by simply telescoping the housings and main tilting slat upon the head bar, and capable of being hung and adjusted within a window casing by unskilled persons with maximum safety and accuracy by simply hanging the head bar structure with its suspended slats and 30 operating cords on the bracket hooks and inserting the clamping screws to lock the head bar in position on the brackets. Moreover, I have described a structure in which the parts thereof can easily be painted and by the use of standard 35 square nuts, as above described, avoid the difficulties attending the assembly of parts having paint filled tapped holes therein.

While I have described what seems now to be the preferred embodiments of my invention, it is conceivable that various modifications in the configuration, composition and disposition of the component elements going to make up the same may occur to those skilled in the art, and no limitation is intended by the phraseology of the 40 foregoing description or illustrations in the accompanying drawings.

What is claimed is:

1. A head bar and housing unit for Venetian blinds comprising a channel bar having a horizontal web and vertical front and rear walls, and a housing at each end of said bar having a pair of wings having a sliding fit laterally between said front and rear walls said housings being secured by cooperation between the lower edges 55 of said wings and the horizontal web.

2. A head bar construction for Venetian blinds comprising a channel bar having a horizontal web and vertical front and rear walls extending beyond the web and having inturned flanges, and 60 a housing at each end of said bar having a sliding fit between the projecting front and rear walls, and said housings having a pair of wings projecting within the bar and having a sliding fit laterally between said front and rear walls and 65 vertically between said web and inturned flanges.

3. A head bar construction for Venetian blinds comprising a channel bar having a horizontal web and vertical front and rear walls extending beyond the web and having inturned flanges, a 70 housing at each end of said bar having a sliding

fit between the projecting front and rear walls, and said housings having a pair of wings projecting within the bar and having a sliding fit laterally between said front and rear walls and vertically between said web and inturned flanges, 5 and tongues for locking said housings in position between said walls.

4. A head bar construction for Venetian blinds comprising a channel bar having a horizontal web and vertical front and rear walls extending beyond the web and having inturned flanges, a housing at each end of said bar having a sliding fit between the projecting front and rear walls, and said housings having a pair of wings projecting within the bar and having a sliding fit 10 laterally between said front and rear walls and vertically between said web and inturned flanges, and tongues projecting longitudinally from the ends of said walls for locking said housings in 15 position.

5. A head bar construction for Venetian blinds comprising a channel bar having a horizontal web and vertical front and rear walls having inturned flanges, a housing at each end of said bar provided with wings having a sliding fit laterally 20 between said front and rear walls and vertically between said web and inturned flanges, and a hole near each end of the rear wall adapted to register with a hole in the adjacent housing wing, in combination with a pair of head bar 25 brackets each having a hook adapted to enter the holes for supporting the head bar and housings. 30

6. A head bar construction for Venetian blinds comprising a channel bar having a horizontal web and vertical front and rear walls having inturned flanges, a housing at each end of said bar provided with wings having a sliding fit laterally 35 between said front and rear walls and vertically between said web and inturned flanges, and a hole near each end of the rear wall adapted to register with the hole in the adjacent housing wing, in combination with a pair of head bar brackets 40 each having a hook adapted to enter the holes for supporting the head bar and housing at the rear, and each bracket having a front flange extending parallel to the front wall of the head bar, and means for clamping the head bar and housing to 45 said bracket flanges.

7. A head bar construction for Venetian blinds comprising a channel bar having a horizontal web and vertical front and rear walls having inturned flanges, a housing at each end of said bar provided with wings having a sliding fit laterally 50 between said front and rear walls and vertically between said web and inturned flanges, a hole near each end of the rear wall adapted to register with a hole in the adjacent housing wing, and recesses in the front walls of said housing for seating screw threaded nuts registering with 55 holes in the front walls of the head bar, in combination with a pair of head bar brackets each having a hook adapted to enter said holes for supporting the head bar and housing at the rear, and each bracket having a slotted front flange 60 extending parallel to the front wall of the head bar, and headed screws passing through said slots and head bar holes and engaging said nuts for adjustably clamping the head bar and housing to 65 said bracket flanges.

8. A slat tilting mechanism for a Venetian blind, comprising a housing, a disk journaled in said housing, tilting cords attached to and coiled on opposite sides of said disk in opposite direc- 70

- tions, and a tilting slat operatively connected with said disk.
9. A slat tilting mechanism for a Venetian blind, comprising a housing, a disk journaled in said housing, tilting cords attached to and coiled on said disk in opposite directions, a pinion operatively connected with said disk, a gear segment pivoted on said housing and meshing with said pinion, and means on said gear segment for 10 engaging a tilting slat.
10. A slat tilting mechanism for a Venetian blind, comprising a housing, a disk journaled therein, tilting cords attached to and coiled on said disk in opposite directions, a pinion operatively connected with said disk, a gear segment pivoted on said housing and meshing with said pinion, a brake engaging said disk, and means on 15 said gear segment for engaging a tilting slat.
11. A housing for the tilting mechanism of a Venetian blind, comprising a body part having front and rear walls projecting at right angles to the body and which walls are extended to provide supporting wings for insertion into a head bar, a cover member between which and the body 20 part the mechanism is supported, and a recess on the front wall for retaining a locking nut.
12. A head bar construction for Venetian blinds 25 comprising a generally channel-shaped bar having each end thereof formed for a slidably gripping engagement with a housing, in combination with a housing mounted at each end of said bar, each of said housings having means projecting laterally therefrom and adapted to slide snugly 5 into the ends of said channel bar whereby said housings are held against a movement of rotation with respect to said head bar.
13. A Venetian blind head bar unit comprising 10 in combination a head bar having the ends thereof adapted for a slidably gripping engagement with a portion of a housing, a Venetian blind slat, a housing mounted on and depending from one end of said head bar and adapted to conceal 15 within the same a slat tilting mechanism, a housing mounted on and depending from the other end of said head bar and adapted to conceal within the same an elevating cord locking mechanism, each of said housings having means for 20 rotatably supporting said slat in spaced relation with respect to said bar, and means projecting laterally therefrom and adapted to slide snugly 25 into an end of said bar whereby said housings are held against a movement of rotation with respect to said head bar.

SAMUEL HAMMER.
